TOOL FOR SEGMENTING CITRUS FRUITS

Ralph Polk, Sr., Miami, and Ralph Polk, Jr.,
Haines City, Fla., assignors to The Polk De-
velopment Company, Tampa, Fla., a copartner-
ship of Florida

Original application April 13, 1938, Serial No.
201,732. Divided and this application July 24,
1939, Serial No. 286,204

3 Claims. (Cl. 146—3)

The present application is a division from our co-pending application Serial No. 201,732, which has matured into Patent No. 2,199,345, April 30, 1940 and relates to that portion of the invention which is illustrated in Figs. 3 and 4 of the aforesaid application.

The object of this invention is to provide a tool of such character that it may be projected between the radially extending divergent portions of a juice-cell-group integument immediately within the apex formed thereby and then so manipulated that a portion of the tool will serve as a holder to prevent outward displacement of the integument while another portion of the tool is swung outwardly in the bonding plane between one of the divergent integument portions and the surface of the juice-cell-group nature bonded thereto, in order to free the juice-cell-group from its nature bond without substantial disruption of the juice cells in the bonding plane.

The accompanying drawing illustrates our invention.

Fig. 1 is a perspective view of our improved tool;
Fig. 2 a transverse section on a larger scale;

Fig. 3 a perspective view, on a smaller scale of our improved tools which may be used simultaneously upon a peeled fruit;

Fig. 4 an enlarged perspective view of a modified tool; and

Fig. 5 an enlarged transverse section of the tool shown in Fig. 4.

In the drawing 10 indicates a head from which depends a rod 11 and a trough-like portion 12 which partially embraces, but is slightly spaced from, rod 11.

Attached to the lower end of rod 11 and trough 12 is a tapered head 13. The head 13, at its larger upper end, preferably, although not necessarily, has a diameter slightly greater than the diameter of trough 12 and an axial extent sufficient to permit a relatively small taper angle, and the axial extent of rod 11 and trough 12 should somewhat exceed the polar diameter of the fruits to be acted upon. Pivoted in head 10, on an axis at right angles to the axis of rod 11 and trough 12, and substantially normal to one edge of the trough, is a thin stripper blade 14 which will lie in a plane substantially parallel with the flare of the trough 12 with its rear edge normally nested between that edge of the trough and the rod 11. Blade 14 has a length which brings its tip fairly close to the upper end of head 13 and a width, at the tip, which, when the blade is in normal position, will be within the diameter of the upper end of head 13. Blade 14 is provided, at its upper end, with

an outwardly projected arm 15, by means of which it may be manipulated to swing about its pivot 16.

In use, head 13 is projected polarwise through the fruit, i. e., parallel with the apex of a juice-cell-group, through the meat of the juice-cell-group immediately within the apex formed by the two radiating portions of the juice-cell-group integument, the stripper knife 14 at that time lying parallel with the main axis of the tool with its lower end guarded by the upper end of head 13. Projection is continued until the lower end of the stripper blade 14 emerges from the lower end of the fruit, whereupon the stripper blade is swung upon its axis so as to swing the stripper blade outward. Preferably, before the projection of the tool into the fruit, a void is formed in the meat of the segment between the radiating portions of the integument so as to eliminate seeds, if they are present, and permit insertion of the tool without bursting the fruit, although, in case of seedless fruits, there are times when the preliminary formation of the above-mentioned void is not necessary. The maximum diameter of the head is such that the above-mentioned projection through the fruit may be accomplished without a material spreading of the radiating integuments and this dimension will, of course, vary with the fruits to be acted upon, grapefruits permitting the use of larger tools than oranges. The trough-like portion 12 serves to position the tool immediately between the radiating portions of an integument and likewise to position the blade 14 substantially in the plane of bond between a radiating integument and the immediately adjacent face of the juice-cell-group so that, after the lower end of the stripper blade has emerged from the lower part of the fruit and outward swinging of the blade is guided by the lateral resistance of the integument, to travel along the inner face, i. e., the bonded face, of the integument and strip the juice-cell-group therefrom.

The tools have some lateral flexibility, because of their length, and if desired the rod 11 may be omitted, as shown in Figs. 4 and 5.

We have found in practice that a circumferential group of tools of this kind, in number about half the number of segments in fruit, may be simultaneously projected through a peeled fruit without rupturing the natural bond between the flaring integument portions of adjacent integuments, the manipulation of this number of tools resulting in a freeing of approximately half of the juice-cell-groups, at one radial face, and a second projection of the tool group resulting in a freeing of the remaining half of the segments.

We claim as our invention:

1. A tool for rupturing the natural bond between one side of a juice-cell-group of a citrus fruit and the adjacent radial integument, comprising a trough-shaped main stem closed at its lower end by a tapered tip and having a length, above the tip, exceeding the polar dimension of the fruit segment, a thin blade nested in the trough-shaped stem above the tip to be normally guarded by said tip, and a pivotal mounting for said blade on a fixed axis transverse of the axis of the stem whereby, after projection of the stem and guarded blade polarwise through the apex of the fruit segment without rupture of the radial integuments, the blade may be swung outwardly to rupture the natural bond between the penetrated juice-cell-group and the adherent radial integument.

2. A tool of the character specified in claim 1 wherein a rod lies axially within the trough but spaced therefrom, and the stripper blade in its unprojected position has its inner edge nested between the rod and trough.

3. A tool for rupturing the natural bond be-

tween one side of a juice-cell-group of a citrus fruit and the adherent radial integument comprising, a main stem having an enlarged dependent tapered lower end, a dependent stripper blade pivoted at its upper end upon a fixed axis at right angles to the axis of the main stem to swing in a plane tangential to and radially spaced from the axis of the main stem, the free lower end of the blade, when in normal retracted position, lying alongside the shank with its tip lying over an exposed portion of the upper end of the enlarged tapered lower end, said shank and lower end having such transverse and longitudinal dimensions that they may be projected polarwise through the apex of a juice-cell-group of a citrus fruit without rupturing the radiating portions of the integument thereof to position the stripper blade substantially in the plane of bond between one side of a juice-cell-group and its adherent radiating integument, and means by which the stripper blade may be swung upon its fixed pivot.
